BOW FOR MUSICAL INSTRUMENTS

Alfred Nathan, London, England, assignor to
 Rose, Morris & Company Limited, London,
 England

Application February 2, 1948, Serial No. 5,793
 In Great Britain May 10, 1946

Section 1, Public Law 690, August 8, 1946
 Patent expires May 10, 1966

10 Claims. (Cl. 84—282)

1

This invention relates to bows for musical instruments. Such bows usually comprise a number of strands of hair or equivalent material which are held in tension by being attached between the frog and the tip of a staff, the frog being longitudinally adjustable relative to the staff so as to enable the tension in the hair or equivalent to be varied.

It is the object of the invention to provide an improved form and construction of adjustable frog which is found to be more satisfactory than those in normal use, especially with respect to the smooth adjustment which it permits; the improved frog can, moreover, be made so as to be very robust and yet light in weight.

According to the invention, in a bow for a musical instrument, the frog comprises a body which extends more than half way around the outside of the staff to retain the latter, the body being slidable longitudinally upon the staff and having means whereby it is located against angular displacement about the axis of the staff.

There is further provided according to the invention in a bow for a musical instrument an adjustable frog comprising a body formed with a socket which extends more than half way around the outside of the staff to retain the latter but allow relative sliding of the frog upon the staff in the longitudinal direction, means to prevent relative angular movement of the frog and staff, and an adjustable thrust member upon the frog arranged to bear against the end part of the staff to locate the frog in the longitudinal direction. Preferably the socket in the body comprises a passage, the wall of which extends completely around the end part of the staff. Preferably also, the body of the frog is screw-threaded at a position beyond the end of the staff, and is there fitted with a thrust screw, the tip of which presses against the end of the staff. The head of the screw may have a cylindrical base which enters a corresponding cylindrical counterbore in the body to avoid exposing the thread of the screw throughout the normal range of adjustment of the frog. Further, the body may be located against angular displacement relative to the staff, by a member which projects inwards through the wall of the socket and engages a longitudinal groove or slot in the end part of the staff. This projection can be constituted by the

2

tip of a screw disposed within a hole in the body, the end of said hole being so disposed that it is covered by the hair of the bow. The staff may advantageously comprise a metal tube having its end closed by a plug which latter is engaged by the tip of the thrust screw. With the present invention the end part of the staff can conveniently be circular in cross section and fit slidably within a cylindrical socket formed in the body of the frog.

As a further aspect of the invention there is provided in a bow for a musical instrument, a frog comprising a body of U-shape having a cylindrical socket bored down one of its limbs 5 from the extremity thereof, a screw-thread extending axially through the base of the socket, a thrust screw fitted into said screw-thread and having its tip disposed within the socket, the staff with its end part slidable longitudinally within the socket but restrained against rotation, and attachment means for the usual hair associated with the other limb of the body.

The preferred form of bow according to the invention is illustrated in the accompanying drawings, in which:

Figure 1 is a side elevation of a musician's bow;
 Figure 2 is a part sectional elevation of the frog and adjacent end of the staff, drawn to an enlarged scale;

Figure 3 is a transverse sectional elevation, taken on the line 3—3 of Figure 2; and

Figure 4 is a view similar to Figure 3 but showing a modified construction.

The bow in Figure 1 comprises a staff 10 which is made of light gauge steel tube, gently tapered in diameter and fitted at its smaller end with a tip portion 11. The staff 10 is circular in cross sectional shape throughout its length and is fitted slidably at its larger end within a frog which is indicated generally at 12 in Figure 1. This comprises a body 13 which is of substantially U-shape, the uppermost limb 14 being used for the attachment of the frog to the staff 10, while the lower limb 15 accommodates one end of the usual band 16 of hairs extending to the tip portion 11. These hairs are secured at their ends to the tip portion 11 and frog 12 respectively and are held under tension by slidably adjusting the frog 12 upon the end part of the staff 10 by means of a rotatable knob or head 17.

The construction of the frog 12 is shown in Figures 2 and 3. The body 13 is made of light metal or alloy and it has its uppermost limb 14 bored at 18 to form a cylindrical socket which snugly receives the end portion 19 of the staff 10. The socket 18 completely surrounds the staff 10 and thus provides a firm connection which however permits the parts to slide telescopically for effecting adjustment of the hair tension. To prevent relative rotation of the parts the portion 19 of the staff 10 is formed with a longitudinal slot 20 which is engaged by the tip portion 21 of a grub screw 22 threaded into a hole 23 in the body 13; the hole 23 extends upwards from a groove 24 in the lower surface of the body 13 so that when the hair 16 is laid in said groove and is protected by the usual cover-strip 25, the screw 22 and its hole are completely concealed. The extremity of the staff 10 is closed by a plug 26 to provide a flat end surface.

The base portion 27 of the socket 18 is drilled axially and screw-threaded at 28 to receive a thrust screw 29 which is integral with or attached firmly to the head 17 and has its tip 30 in engagement with the plug 26 of the staff 10. Thus the staff 10 can be pressed towards the left (to tension the hair 16) by rotating the head 17 so that the screw 29 is advanced; rotation in the reverse direction allows the hair tension to slacken. In order to avoid exposing the screw 29 (and thus keep the threads clean as well as improve the appearance of the bow) the head 17 is formed with a cylindrical base 31 which fits with only slight clearance within a counterbore 32 in the body 13, at least a part of the base 31 being in engagement with the counterbore 32 even when the tension is fully slackened. This also provides a direct bearing for the head 17 and thus prevents any side thrust from bending the screw 29.

It will be understood that the arrangement which has so far been described has been given only by way of example and that various modifications may be made to suit requirements. For instance the improved form of frog may be used in conjunction with staffs made of wood or any other material and where appropriate the slot 20 would be replaced by a longitudinal groove. Moreover, rotation may be prevented by making the end portion 19 of the staff of non-circular cross section and forming the socket 18 to suit; the cylindrical form is at present preferred, however, as it enables an accurate fit to be produced relatively easily. It is not essential that the wall of the socket 18 should extend completely around the portion 19 of the staff as the latter can be retained by making the socket of undercut channel shape, for instance as shown in Figure 4. In this suggested modification the end portion 19a of the staff 10 is of square cross section and the socket comprises side walls 18a having top flanges 18b for positively retaining the staff 10, but allowing it to slide longitudinally. Moreover the body 13 of the frog shown in Figures 2 and 3 may be bored from end to end to form the socket 18 and the counter bore 32, the base 27 carrying the screw thread 28 being made separately and secured in position; if desired it may be made of hard-wearing material such as brass to give long life to the thread.

What I claim is:

1. A musical instrument bow comprising a staff having a tip and a frog at opposite ends for the attachment of the usual hair, said frog including a body having a socket formed therein and slid-

able upon the end of the staff, the walls of the socket extending more than half way around the outside of the staff to secure the frog to the staff, means for preventing rotation of the frog around the staff, and adjusting means for regulating the longitudinal position of the frog upon the staff.

5 2. A musical instrument bow comprising a staff having a tip and a frog at opposite ends for the attachment of the usual hair, said frog including a body having a socket formed therein and slid- 10 able upon the end of the staff, the walls of the socket extending more than half way around the outside of the staff to secure the frog to the staff, means for preventing rotation of the frog around 15 the staff, and an adjusting screw threaded into the body with its tip projecting axially into the socket and engaging with the end of the staff.

15 3. A musical instrument bow according to claim 2, wherein the staff is tubular, a plate being 20 secured across the end of said staff and acting as an abutment for the screw.

25 4. A musical instrument bow comprising a staff having a tip and a frog at opposite ends for the attachment of the usual hair, said frog including a body having a socket formed therein and slid- 30 able upon the end of the staff, the walls of the socket extending completely around the outside of the staff to secure the frog to the staff, means for preventing rotation of the frog around the staff, and adjusting means for regulating the longitudinal position of the frog upon the staff.

35 5. A musical instrument bow comprising a staff having a tip and a frog at opposite ends for the attachment of the usual hair, said frog including a body having a socket formed therein and slid- 40 able upon the end of the staff, the walls of the socket extending more than half way around the outside of the staff to secure the frog to the staff, a slot in the side of the staff, a key member mounted on the body and projecting into the socket to engage within the slot to prevent relative rotation between the staff and the body, and adjusting means for regulating the longitudinal position of the frog upon the staff.

45 6. A musical instrument bow comprising a staff having a tip and a frog at opposite ends for the attachment of the usual hair, said frog including a body having a socket formed therein and slid- 50 able upon the end of the staff, the walls of the socket extending more than half way around the outside of the staff to secure the frog to the staff, a slot in the side of the staff, a key member mounted on the body and projecting into the socket to engage within the slot to prevent relative rotation between the staff and the body, and adjusting means for regulating the longitudinal position of the frog upon the staff, the engagement of the key member with the slot preventing endwise detachment of the body from the staff.

55 7. A musical instrument bow according to claim 6, wherein the key member comprises a grub screw, threaded into the body and having its tip projecting into the socket.

60 8. A musical instrument bow comprising a staff having a tip and a frog at opposite ends for the attachment of the usual hair, said frog including a body having a cylindrical socket formed therein and which slidably fits over that end of the staff remote from the tip, means for preventing rotation of the frog around the staff, and adjusting means for regulating the longitudinal position of the frog upon the staff.

65 9. For a musical instrument bow, a frog comprising a U-shaped body with two limbs extending side by side from a base portion, a cylindrical

socket formed in one of said limbs and extending longitudinally thereinto from the extremity of said limb, and having an end wall, an adjusting screw extending into said one limb from the base end thereof and projecting axially through the said end wall, and means on the other limb for holding the usual hair of the bow.

10. For a musical instrument bow, a frog according to claim 9, wherein a cylindrical counterbore is formed in the base portion in alignment with the axis of the cylindrical socket, and the adjusting screw has a cylindrical head portion of substantial length arranged to extend

into said counterbore throughout the full range of adjustment of the screw.
